US0D1078745S

(12) **United States Design Patent** (10) Patent No.: **US D1,078,745 S**
(45) Date of Patent: ** Jun. 10, 2025

(54) **MONITOR STAND**

(71) Applicant: **ANHUI HONGJIE ERGONOMIC TECHNOLOGY CO., LTD.**,
Xuancheng (CN)

(72) Inventor: **Xiaojie Chang**, Anhui (CN)

(***) Term: **15 Years**

(21) Appl. No.: **35/521,147**

(22) Filed: **Apr. 10, 2024**

(80) **Hague Agreement Data**

Int. Filing Date: **Apr. 10, 2024**

Int. Reg. No.: **DM/237266**

Int. Reg. Date: **Apr. 10, 2024**

Int. Reg. Pub. Date: **Jun. 7, 2024**

(30) **Foreign Application Priority Data**

Nov. 7, 2023 (CN) 202330725399.X

(51) **LOC (15) Cl.** **14-02**

(52) **U.S. Cl.**

USPC **D14/452**
